UNITED STATES PATENT OFFICE.

WILLIAM C. HOPSON, OF GRAND RAPIDS, MICHIGAN, ASSIGNOR TO W. C. HOPSON COMPANY, OF GRAND RAPIDS, MICHIGAN.

ROOF FLASHING.

Application filed April 11, 1923. Serial No. 269,173.

The main object of this invention is to provide an improved roof flashing which is highly efficient for the purpose and at the same time is economical in structure and 5 easily adjusted to meet roof conditions and to the flue associated therewith.

Objects pertaining to details and economies of my invention will appear from the description to follow. The invention is defined 10 in the claims.

A structure embodying the features of my invention is clearly illustrated in the accompanying drawing forming a part of this application, in which:

15 Fig. 1 is a side elevation of my improved roof flashing shown in operative relation to a flue.

Fig. 2 is a vertical central section on a line corresponding to line 2—2 of Figs. 3 and 4.

20 Fig. 3 is a detail vertical section on a line corresponding to line 3—3 of Fig. 2.

Fig. 4 is a fragmentary view looking from the right of Fig. 2.

25 Fig. 5 is an enlarged detail on line 5—5 of Fig. 4.

Referring to the drawing, 1 represents a pipe or flue which I have shown in order to clearly illustrate the use of my improved 30 flashing. My improved flashing comprises a base member designated generally by the numeral 2 and having opposed flat side walls 3 and cylindrically curved upwardly converging end walls 4. These walls are provided with flanges 5 at their lower ends. The top member designated generally by the numeral 35 6 has flat side walls 7 embracing the side walls of the base member and pivoted thereto at 8, the lower edges 9 of the side walls being preferably upwardly inclined thereby permitting 40 the arrangement of the pivot well toward the bottom of the base member and the swinging of the top member on the pivot.

The end walls 10 and 11 of the top member 45 are also preferably substantially flat and are upwardly inclined. The upper portion of the ends and side walls of the top member is shaped into a cylindrical form to receive a round pipe.

The top member is preferably formed of a 50 single sheet of material with the edges 12 and 13 of the sheet overlapping, the edge 12 being folded upon itself to form a seam channel 14 into which the edge 13 projects. These overlapping seam parts are pivoted at 15

adjacent the lower edge of the top member 55 and are provided with opposed ears 16 adjacent their upper ends through which the clamping bolt 17 is arranged so that the top member may be clamped upon the pipe or flue as one.

I preferably provide a gasket or packing 60 18 which is of U cross section and arranged over the upper edge of the top member so as to render the joint substantially watertight.

To support the top member in its adjusted positions I provide the base member with a bolt 19 which is disposed through a slot 20 concentric of the pivot 8, a winged clamping nut 21 being threaded upon the end of the 70 bolt to clamp the walls together, thereby effectively supporting the parts.

My improved flashing is economical in its parts and is effective in excluding water. It 75 may be easily applied and adjusted, or installed and adjusted, to the pitch of the roof and has a substantial range of adjustment to the flue.

Having thus described my invention what I claim as new and desire to secure by Letters Patent is:

1. An adjustable roof flashing comprising a base member having flat parallel side walls and cylindrically curved end walls, a top member having opposed substantially parallel side walls and downwardly inclined substantially flat end walls embracing the corresponding walls of said base member, the upper portions of said side and end walls being conformed to approximately circular form, said side and end walls of said top member being formed of a single sheet of material having overlapping vertical edges disposed centrally of one of the end walls, said overlapping edges being conformed to provide a telescoping seam joint and being pivotally connected adjacent their lower ends, clamping ears disposed in opposed relation to the adjacent edges of said top member adjacent the top thereof, a clamping bolt co-acting with said ears, whereby the top member may be clamped upon a flue, pivots connecting the side walls of said top member to the side walls of said base member disposed centrally thereof and adjacent to their lower edges, one of said side walls of said top member being slotted, and a bolt on one of the base member side walls disposed

through said slot and provided with a clamping nut whereby the top member is adjustably supported on its pivot.

2. An adjustable roof flashing comprising a base member having flat parallel side walls and cylindrically curved end walls, a top member having opposed substantially parallel side walls and downwardly inclined substantially flat end walls embracing the corresponding walls of said base member, the upper portions of said side and end walls of said top member being conformed to approximately circular form, said side and end walls of said top member being formed of a

single sheet of material having overlapping vertical edges disposed centrally of one of the end walls, said overlapping edges being conformed to provide a telescoping seam joint and being pivotally connected adjacent their lower ends, clamping ears disposed in opposed relation on the adjacent edges of said top member adjacent the top thereof, and a clamping bolt coacting with said ears whereby the top member may be clamped upon a flue. 15

In witness whereof I have hereunto set my hand.

WILLIAM C. HOPSON.
